UNITED STATES PATENT OFFICE

ALBERT S. HOWELL, OF CHICAGO, ILLINOIS, ASSIGNOR TO THE BELL & HOWELL COMPANY, OF CHICAGO, ILLINOIS, A CORPORATION OF ILLINOIS

TRIPOD

Application filed October 21, 1929. Serial No. 401,022.

My invention relates particularly to tripods for photographic cameras, although not limited to this use alone.

The principle object of my invention resides in the provision of a novel and dependable tripod which is rigid, light in weight and convenient in use, with a view particularly toward the production of an all metal tripod.

With this object in view my invention consists in certain features of novelty in the construction, combination and arrangement of parts by which the said object and certain other objects hereinafter appearing, are effected, all as fully described with reference

15 to the accompanying drawings and more particularly pointed out in the appended claims.

In the said drawings—

Figure 1 is a perspective view of a tripod embodying my invention and set up ready 20 for use;

Figure 2 is a side elevation of the tripod when folded;

Figure 3 is a condensed longitudinal section of a portion of one of the legs of the 25 tripod;

Figure 4 is a bottom view of the head structure of the tripod;

Figure 5 is an axial sectional view of the aforesaid head structure; and

30 Figure 6 is a section on the line 6—6 of Figure 3.

Like characters of reference indicate like parts in the several views.

Referring to the drawings, the tripod consists generally, as is usual, of a head structure upon which a photographic camera or other device may be detachably mounted and to which three extensible supporting legs are pivotally attached, as will be observed from 35 Figures 1 and 2.

These extensible legs are identical, in view of which but one will be described, it being understood that the description applies to all, and the same reference characters on the drawings indicating like parts thereof.

Referring particularly to Figure 3, a leg involves an upper tube 1 and a smaller lower tube 2 telescopically engaged within the upper tube for sliding movement, the upper 40 end of the lower tube being expanded, as

designated at 3, to have a sliding fit with the main portion of the upper tube, and the lower end of the upper tube being contracted, as designated at 4 to have a sliding fit with the main portion of the lower tube below the expanded portion 3 thereof.

The portion of the tube 1 between the normal portion and the contracted lower end 4 thereof is in the form of a taper portion 10, while the portion of the tube 2 between the normal portion and the expanded upper end 3 thereof is in the form of a taper portion 20 engageable within the taper portion 10 when the tubes are extended, to provide a shoulder stop limiting extending movement of the tubes, which engagement, by reason of the taper shoulder engagement, prevents relative lateral movement of the tubes at this point, as shown in Figure 3, the construction providing a bearing engagement, between 70 the tubes, of constant length and giving the leg structure a tapering appearance when extended.

The upper and lower tubes 1 and 2 are adjustably fixed with one another for adjusting the length of the leg in the following manner.

The upper end portion of the inner tube 2 engaged within the tube 1 is longitudinally slit by diametrical slots 5, and a tapered expansion cup 6 is disposed within the enclosure of the tubes and is engageable downwardly upon the slit upper end of the inner tube to expand the slit upper end portion thereof against the outer tube 1 to fix the tubes in adjusted positions throughout their relative movement.

Upward movement of the cup 6 with reference to the tube 2 releases the tubes for relative movement, and movement of the cup 6 with reference to the tube 2 is conveniently effected in the following manner.

A rod 7 extends within the tube 2 and, having its upper end engaged in a central aperture through the expansion cup 6, is secured therewith longitudinally by means of a head 8 on the rod above the cup 6 and a pair of radial projections 9 swaged on the rod below the cup 6.

The rod 7 extends downwardly from the 100

cup 6 to and below the lower end of the tube 2, and extends for sliding movement through a central aperture in a circumferentially flanged thimble 11 press fitted into the lower 5 reduced end of the tube 2, the rod 7 being prevented from rotation with reference to the thimble and tube 2 by means of keys 12 swaged on the rod and slidably engaging keyways 13 in the thimble. See Figures 3 and 6.

10 A helical spring 14 encircles the rod 7 just above the thimble and reacting thereon operates the rod 7 and with it the cup 6 upwardly by means of a washer 15, also encircling the rod above the spring and engaged 15 thereby, and radial projections 16 swaged on the rod above the washer and engaged thereby.

As actuated upwardly by the spring 14 the cup 6 is moved out of expanding relation with 20 the slit upper end of the tube 2, so that the tubes 1 and 2 may be moved longitudinally with reference to each other for extending or shortening the leg.

25 Downward or expanding movement of the rod 7 and cup 6 is effected manually in the following manner.

The rod 7 extends below or outwardly of the lower end of the tube 2 with a screw-threaded portion 17, and screwthreaded upon 30 this portion 17 is a tip member 18 which is pointed at its lower end for non-slipping engagement on the surface upon which the tripod rests when set up.

35 Press fitted upon a reduced and shouldered upper portion of the tip member 18, by means of an axial bore therethrough, is a cup shaped manipulating member 19 the flange of which extends upwardly about the lower end of the tube 2.

40 The manipulating member 19 bears upwardly against the thimble 11, and rotation of the manipulating member in one direction acts upon the rod 7 to pull it, and with it the expansion cup 6, downwardly, whereby to 45 expand the slit upper end of the tube 2 against the tube 1 to fix the tubes in the desired relative position.

Rotation of the member 19 in the opposite direction permits the spring 14 to actuate the 50 rod 7, and with it the cup 6, upwardly, whereby to move the cup 6 out of expanding relation with the slit upper end of the tube 2 to permit relative movement of the tubes 1 and 2.

55 Springs 21 of U-shape are disposed adjacent the upper end of the tube 2, and being disposed diametrically thereof engage in diametrically opposite slots 5 and against the 60 outer tube 1 to provide a constant initial friction on the tube 1 to prevent rotation of the tube 2 during manipulation of the member 19, these springs being confined longitudinally with the tube 2 by reason of the fact 65 that they are engageable with the bottoms

of the slots 5 and with the cup 6 which moves with the tube 2 relative to the tube 1.

A collar 22 is secured on the rod 7 immediately below the keys 12 of the rod and is adapted to abut the thimble 11 to prevent derangement of the rod 7 in the event that the members 19 and 18 are unscrewed too far or removed from the rod.

70 It will be observed, that the leg is readily adjustable, the securing mechanism, with the exception of the manipulating member 19, being enclosed within the tube structure with obvious advantages; that the structure affords rigidity and simplicity in appearance and permits the holding of the legs in compact adjacent parallelism, as shown in Figure 2; and that there are no inconvenient lateral projections on the leg structure.

75 It will be observed that when a leg is extended and the upper end of the inner tube 2 expanded against the upper tube 1, as shown in Figure 3, the taper shoulder engagement, afforded by the taper portions 10 and 20 of the tubes, is free of lost motion while the tubes are at the same time clamped 80 together above the taper engagement, thus 90 providing a rigid joint.

85 A cup shaped cap member 23 is screw-threaded by means of the lip portion thereof on the upper end of the upper tube 1 of the leg, and is provided with a diametrical slot 24 through the closed end portion thereof. 95 See particularly Figures 4 and 5.

90 A pivot member 25, preferably formed of a plate of sheet metal, has a flat portion thereof engaged in said slot. Shoulders 26 are formed on the flat portion of the pivot member and engage the cap member at the ends of the slot 24 for preventing lateral movement of the pivot member in the slot, and lugs 27, formed on said portion of the pivot member intermediate said shoulders and disposed interiorly of the cap member, are oppositely bent against the cap member for securing the pivot member, engaged in the slot, with the cap member.

100 Thus the pivot member is adequately secured with the upper tube 1 of the leg, the cap member providing a suitable termination of the upper end of this tube.

105 The pivot member 25 is bifurcated above the cap member 23 and the spaced portions thereof are circularly bent, as designated at 28, to form alined holes, and a pin 29 extends across between said spaced portions and is 110 engaged in said holes for purposes herein-after described.

115 The head of the tripod is designated generally at 31 and is preferably formed of sheet metal. See Figures 1, 2, 3 and 4.

120 It consists of a central circular portion 32, a downwardly offset portion 33 surrounding the central portion, and a downwardly projecting marginal flange 34 which has three straight portions 35 disposed in equally 130

spaced angular relation. See Figures 4 and 5.

A spring member 36, formed of flat stock, is provided with three radial arms 37 equally spaced angularly thereabout. This spring member is secured, centrally thereof and of the head 31, upwardly against the central portion 32 of the head in the following manner.

A stud 38, provided with an intermediate 10 enlargement 39, has one portion thereof passed downwardly through axial apertures in the central portions 32 of the head and of the spring member 36, and a nut 41 is screw-threaded on the lower end of the stud and 15 clamps the head, the spring, and a washer 42 between it and the intermediate enlargement 39 of the stud. See Figure 5.

The arms 37 of the spring member 36 are disposed correspondingly with the straight 20 portions 35 of the flange 34 of the head, and are formed so that they radially engage the pins 29 upwardly, between the spaced portions of the bifurcated pivot members 25, for maintaining the circularly bent portions 28 25 of the pivot members upwardly against the lower surface of the offset portion 33 of the head and against the straight portions 35 of the flange 34 to form pivotal connections between the head and the legs of the tripod.

30 Thus are provided simple and effective pivotal connections between the head and the legs of the tripod, which provides a desirable friction, these joints providing for the folding of the tripod and the spreading of the 35 legs as desired. See Figures 1 and 2.

The stud 38 extends upwardly from the enlargement 39 thereof and from the head 31, and this portion of the stud is screw-threaded, as designated at 43, for the mounting 40 of a device, such as a photographic camera, upon the head of the tripod.

While I have described and shown the preferred embodiment of my invention I do not wish to be limited to the precise details of 45 construction as changes may readily be made without departing from the spirit of my invention, but having thus described my invention, I claim as new and desire to secure by Letters Patent the following:

50 1. In a tripod leg the combination with a pair of tubes telescopically engaged for sliding movement and the inner of which has a longitudinally slit end portion engaged in the outer tube, of an expansion member with- 55 in the enclosure of said tubes at said slit end portion and movable longitudinally of said inner tube for expanding said slit end portion against the outer tube and releasing the same, an exposed manually operable member 60 at the other end of said inner tube and rotatable with respect thereto, a rod extending within said inner tube and connected with said expansion member for operating the same in its said movement, a helical spring 65 encircling said rod for operating the same in

a direction inwardly from said other end of said inner tube, and a screw connection between said manually operable member and said rod whereby said expansion member is controlled by said manually operable member. 70

2. In a tripod leg the combination with a pair of tubes telescopically engaged for sliding movement and the inner of which has an expansible portion engaged in the outer tube, 75 of an expansion member within the enclosure of said tubes and movable longitudinally of said inner tube for expanding said expansible portion thereof against the outer tube and releasing the same, a rod extending within said inner tube and connected with said expansion member for operating the same, a bearing at the outer end of said inner tube and having engagement with said rod for longitudinal movement of the rod and to prevent rotation thereof with reference to said inner tube, a helical spring encircling said rod inwardly 80 of said bearing for operating the rod in a direction inwardly from the outer end of said inner tube, and a manually operable member 85 having a screwthreaded engagement with the outer end of said rod for operating the rod against the influence of said spring. 90

In witness whereof I hereunto affix my signature this 10th day of October, 1929.

ALBERT S. HOWELL.
